CLAIM

The ornamental design of a sports training device, as shown and described.

DESCRIPTION

FIG. 1 is a perspective view showing a design for a sports training device;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view of the sports training device in use; and,

FIG. 9 is a front view of the sports training device in use. The broken lines shown in the figures are for the purpose of illustrating portions of the sports training device, which form no part of the claimed design. The additional broken lines shown in FIGS. 8 and 9 are for the purposes of illustrating environmental structure, which form no part of the claimed design.
